UNITED STATES PATENT OFFICE.

WARREN M. ABBOTT, OF PHILADELPHIA, PENNSYLVANIA.

VAPOR-BURNER.

SPECIFICATION forming part of Letters Patent No. 373,874, dated November 29, 1887.

Application filed July 20, 1886. Serial No. 208,547. (No model.)

To all whom it may concern:

Be it known that I, WARREN M. ABBOTT, a citizen of the United States, and a resident of Philadelphia, in the county of Philadelphia and State of Pennsylvania, have invented certain new and useful Improvements in Vapor-Burners; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a vertical sectional view. Fig. 2 is a horizontal section. Fig. 3 is a section, and Fig. 4 is a detail.

My invention relates to vapor-burners designed to utilize oil and water as fuel; and it 20 consists in the construction and novel combination of parts, as hereinafter described, and pointed out in the claim.

Referring by letter to the accompanying drawings, S designates the base, on which the 25 jacket J is supported, being secured thereto in the ordinary manner of constructing this class of heaters.

T designates the water-pipe, which passes up through the base S and is provided on its 30 upper end with a water-chamber, B, having a flat perforated top, H, and is provided, also, with a filling of sheet-asbestos, X, rolled in scroll form and inserted in said chamber.

My experiences with this class of burners has 35 taught me that they will work very nicely when regulated properly until it becomes necessary to change the water-supply. Then the water, coming in contact with the hot iron of the water-chamber, will cause an irregular 40 flame to issue from the burner, which will frequently blow the fire out. By the introduction of the asbestos, X, into said water-chamber when more water is added the asbestos prevents the sudden increase of vapor; or, 45 rather, when the water strikes the hot asbestos in the water-chamber the asbestos causes just resistance enough to prevent the blowing above referred to, and the steam passing up through the asbestos becomes rarefied and 50 passes through the perforated top H steadily.

As the steam passes through the asbestos, the latter, being very hot, converts the steam into

a perfect vapor before it leaves the water-chamber, thereby putting it into a condition to mingle thoroughly with the vapor from the oil, which passes up through the oil-pipe C into the mixing-chamber or retort A, in which chamber A said oil is converted into vapor by the heat in the mixing-chamber A, thus providing for a thorough combustion.

55 F F designate the T-heads, through which the vapors from the oil and water pass out of the burner.

The hole for the water-pipe is made, preferably, in the center of the base S, and the hole 65 for the oil-pipe is made near to the first hole. The holes in the bottom of the mixing-chamber are threaded, and the water-chamber and the upper end of the oil-pipe are threaded to engage the threads of said holes.

70 G designates the drip-cup, which is connected to the jacket J and is provided with air-holes K, which permit air to communicate with the fire to promote combustion. The perforated cap H is connected to the water-chamber by 75 screw-threads.

I designates a deflector which is placed on top of the burner and may be moved at pleasure.

The jacket J sits on top of the drip-cup and 80 extends up to within one-half or three-fourths of an inch of the top of the burner or deflector, and holds the fire or flame up next to the generator or retort.

The whole burner or retort may be placed 85 in a stove or any other appropriate place for use.

In operation oil is admitted through a supply-pipe to the mixing-chamber or retort, where it accumulates on the bottom and passes 90 down through pipes to the T-heads, and out through the orifices in the T-heads into the drip-pan G. The oil is then set on fire by a taper or lighted match. The water is turned on when the fire is lighted. The burning oil 95 in a very few minutes converts the water and oil into their respective vapors as fast as they flow into their respective chambers or vessels. The vapor from the water-chamber passes through the perforated cap H on top of the 100 water-chamber with such force that it becomes thoroughly commingled with the vapor generated from the oil in the mixing-chamber, and together the vapors enter the pipes con-

necting the T-heads with the mixing-chamber and pass out through orifices in the T-heads, where they are burned. Thus the combustion of the oil begins the generation of the vapor of the oil and water chambers, and the burning of the vapor continues its production until the supply of oil and water is shut off.

I am aware that vapor-burners of a similar character to mine are common; but none of said burners of similar construction are provided with air-inlets in their side walls, nor with a tube filled with asbestos.

Having described this invention, what I claim, and desire to secure by Letters Patent, 15 is—

In a vapor-burner, the combination of the cupped base, the jacket rising therefrom and

provided with air-inlets at its lower end, a water-pipe provided with an enlarged water-chamber filled with asbestos, a removable perforated cap for this chamber, a retort, A, receiving said water-chamber and provided with a horizontal deflector, an oil-supply pipe leading into said retort, and the perforated T-heads in the drip-pan communicating with the said 20 retort, all constructed and adapted to operate substantially as described.

In testimony whereof I affix my signature in presence of two witnesses.

WARREN M. ABBOTT.
